UNITED STATES PATENT OFFICE.

GEORGE W. FITZ, OF BOSTON, MASSACHUSETTS, AND FREDERIC WADE HITCHINGS, OF CLEVELAND, OHIO.

MASSAGE APPARATUS.

No. 851,510.

Specification of Letters Patent.

Patented April 23, 1907.

Application filed March 3, 1906. Serial No. 304,126.

To all whom it may concern:

Be it known that we, GEORGE W. FITZ, of Boston, in the county of Suffolk and State of Massachusetts, and FREDERIC WADE HITCHINGS, of Cleveland, in the county of Cuyahoga and State of Ohio, have invented certain new and useful Improvements in Massage Apparatus, of which the following is a specification.

10 This invention relates to a massage apparatus, and has for its object to enable heat and mechanical vibration to be applied simultaneously to the human body in the treatment of disease.

15 The invention consists first in an apparatus of the character specified, comprising an applicator, means for vibrating it, and means for applying heat to its acting surface.

20 The invention also consists in an applicator adapted to be attached to mechanism for vibrating it, and provided with an internal chamber or cavity adapted to contain a medium for heating its acting surface.

25 The invention also consists in an applicator provided internally with a heater, which includes an electrical resistance, the said heater being adapted to impart heat to the acting surface of the applicator.

30 Of the accompanying drawings forming a part of this specification,—Figure 1 represents a side elevation of a massage apparatus or vibrator, provided with an applicator embodying our invention. Fig. 2 represents a perspective view of the applicator detached.

35 Fig. 3 represents a longitudinal section of the applicator. Fig. 4 represents an end view of the same. Fig. 5 represents a section on line 5—5 of Fig. 3. Fig. 6 represents an end view of the electric heater. Fig. 7 represents an enlargement of a portion of Fig. 3. Figs. 8 and 9 represent sectional views of modifications.

40 The same letters of reference indicate the same parts in all the figures.

45 Our improved applicator is here shown as composed of a hollow shell 12 of metal or other suitable material, having at one end an internally threaded socket 13 for engagement with the externally threaded end of a

50 rod or shank 14, forming a part of the vibrating apparatus. The said apparatus may be of any suitable construction, such, for example, as that shown in Letters Patent of the United States to George W. Fitz, No. 795,212,

to which reference may be had for a full description. 55

In the embodiment of our invention, shown in Figs. 1 to 6 inclusive, the shell 12 is provided with a removable end piece or head 15, on which the socket 13 is formed, said head 6c having a screw thread or other detachable connection with the body of the shell. Within the shell is an electric heater, comprising a resistance coil 16 and suitable means for supporting the same within the shell. The convolutions of the coil are preferably disposed in a series of concentric layers, separated from each other by annular layers 18 of sheet mica, the wire of the coil being continuous and extending from layer to layer through or 70 across the intermediate separating layers 18. The resistance coil is supported by a spool, comprising a central rod or core 19, having at one end a screw thread to engage the inner portion of the threaded socket 13, and at its 75 opposite end a head or enlargement, a sleeve 20, mounted on the core 19, and end pieces or heads 21, 22 affixed to the sleeve 20. 23 represents a disc or plate, which is preferably of annular form, and is made of insulating material, preferably of vulcanized fibre. This plate supports two binding posts or screws 24—24, which bear upon contact plates 25—25, affixed to the head 21, said contact plates being in electrical connection with the terminal portions 160 of the coil wire 16. The 80 binding posts 24 are adapted to engage flexible conducting wires 26, which are enclosed in a cable 27, the latter passing through an orifice 28 in the removable end piece 15. The 85 wires 26 are connected with the binding posts or screws 24. The flexible conducting wires 26 are connected with a suitable source of electricity, the connection being through a suitable switch, whereby the current may be 90 turned on and off. 95

It will be seen that when the resistance coil is electrified, the heat developed is radiated and conducted to the shell 12 so that the latter imparts heat to the body being operated 100 upon. This simultaneous application of heat and mechanical vibration is useful in the treatment of various diseases.

While we prefer electrical means for heating the applicator, we do not limit ourselves 105 thereto, as the applicator may be heated in any other suitable way; for example, by inserting heated water or other liquid in the

shell through an orifice 31, said orifice being provided with a suitable stopper 32, as shown in Fig. 8. In Fig. 9 we show an applicator adapted to be heated externally by the impingement of a gas or other flame upon its external surfaces. In this case the shell is made in two sections separably connected at 32, so that the shell may be conveniently filled with asbestos, powdered soap stone, sand or any other heat retaining substance.

The heat developed by the electrical heater or resistance coil may be regulated in various ways; for example (a) by varying the length and size, or both, of the wire composing the said coil; (b) by varying the length of time the current is allowed to run through the coil; (c) by placing a supplemental resistance coil between the switch and the main resistance coil, and (d) by placing an automatic cut-off thermostat between the switch and the resistance coil.

It will be seen that the spool or holder on which the resistance coil is mounted is adapted to be readily attached to and detached from the casing of the applicator, so that the removal of the coil for examination and the substitution of a fresh coil is a comparatively simple matter. The cable 21 is preferably reinforced at the point where it joins the casing and for a short distance adjacent thereto by a wrapping 35 of wire, as shown in Fig. 2.

The hollow applicator formed as shown in Figs. 8 and 9 may be heated by means of a chemical solution or composition, which is of such nature that heat will be generated and maintained for a considerable period by the crystallization of a crystallizable ingredient or ingredients of the composition.

We believe ourselves to be the first to provide an applicator or massage appliance with an electric heater located in close proximity to the acting surface of the applicator. We do not, therefore, limit ourselves to an electrically heated applicator provided with means for engagement with mechanism for vibrating it, as the applicator may be provided with means whereby it may be operated by hand.

We claim:

1. An apparatus for the treatment of disease, comprising an applicator, means for positively vibrating it and means for applying heat to its acting surface.

2. An applicator having means for holding a heating medium in operative relation to its acting surface, and means for engagement with a device or mechanism for positively vibrating the applicator.

3. An applicator having an electrical heater operatively related to its acting surface, means for positively vibrating the applicator and flexible conducting wires electrically connected with the heater and extending therefrom.

4. An applicator having a cavity or chamber, means for vibrating the applicator, an electrical resistance coil located in said chamber, and flexible conducting wires electrically connected with said coil.

5. An applicator having a resistance coil operatively related to its acting surface, means for vibrating the applicator, means including flexible conducting wires for closing a circuit through said coil and means for regulating the heat developed in said coil.

6. An applicator comprising a hollow casing, means for vibrating it, an electrical heater comprising a resistance coil adapted to enter said casing, and means for detachably securing the coil to the casing.

7. An applicator comprising a hollow casing, means for vibrating it, an electrical heater comprising a resistance coil adapted to enter said casing, a spool or holder supporting said coil and having a core or stem detachably engaged with the casing.

8. An applicator comprising a hollow casing means for vibrating it, said casing having a detachable end piece or head adapted for detachable connection with the vibrating means, and a holder detachably secured to said head and supporting a resistance coil.

9. An applicator, comprising a hollow casing, having a detachable end piece or head, provided with an internally threaded socket, a holder adapted to detachably engage the said socket, and a resistance coil supported by the holder, and means engaging said socket to vibrate the applicator.

10. An applicator having an internal electrical heater, flexible conducting wires electrically connected with the heater and extending from the applicator, and a flexible cable enclosing the said wires and provided with a wire wrapping at and adjacent to its junction with the applicator, and means for vibrating the applicator.

11. In combination, an applicator, an electrical heater operatively related to the acting surface of the applicator, and means for positively vibrating the applicator.

12. In combination, an applicator, an electric heater operatively related to its acting surface, means for positively vibrating the applicator and heater, and flexible conducting wires connected with the heater and extending therefrom.

In testimony whereof we have affixed our signatures, in presence of two witnesses.
